GRINDING MACHINE

John J. Keller, Hauppauge, and Konrad Lober,
Woodhaven, N. Y.

Application November 28, 1945, Serial No. 631,379

6 Claims. (Cl. 51—108)

1

This invention relates to grinding machines and in particular to a type that is particularly adapted to the grinding and shaping of cork articles.

An object of the invention is to produce a compact machine wherein the articles to be shaped are fed to the machine and advance continuously from one position or station to another to provide an output that is at maximum quantity consistent with good grinding work and one to which the articles or rough blanks may be fed either manually or mechanically and can be removed from the machine in the same way without the necessity of slackening the production speed of the machine.

A further object of the invention is to provide means for rough grinding and then finish grinding without the necessity of feeding each blank to the grinding wheels as separate operations, it being our purpose to advance the work orbitally and cause the grinding wheels to engage the work as the latter revolves axially so that saving in time is accomplished, the machine operation is purely automatic and the production is continuous.

A still further object of the invention is to provide a machine in which the grinders are not only fed to the work, but one in which said grinders may be individually adjusted in their feed movements to adapt them to various sizes of grinding jobs, thereby making the machine adjustable to accommodate various sizes and shapes of work. Other features of construction include variable sizes of work removing means into which the work passes to be drawn from the machine.

Other objects of the invention are to provide a simplified drive mechanism for operating the work carrier and the individual work holders so that the latter travel in an orbit while having axial rotation, the latter of which only takes place while the work is in the grinding zone; to provide a sturdy construction that can be readily adjusted and one in which a maximum amount of work in various shapes and sizes may be turned out to constitute what amounts to a universal grinding machine.

With these and other objects in view, the invention comprises certain constructions herein-after described and then particularly pointed out in the claims and a preferred embodiment of my invention is illustrated in the accompanying drawings, in which:

Figure 1 is a top plan view of a machine constructed in accordance with our invention showing the relative position of the parts,

Figure 2 is a view in side elevation of the machine shown in Figure 1,

Figure 3 is an end elevation of the machine shown in Figure 1, the view being taken looking toward the left end of Figure 2,

Figure 4 is a fragmentary detail in end eleva-

2

tion of the work advancing means as seen when viewed from the left of Figure 3.

Figure 5 is a section on the line 5—5 of Figure 2 showing the grinding wheel supports,

Figure 6 is a diagrammatic view of the work holder showing the progress of the work from the point of feed to the point of discharge,

Figure 7 is an enlarged section taken on the line 7—7 of Figure 2 showing the work positioning and discharging members,

Figure 8 is a view in perspective, a part being broken away, of the work removing claw member,

Figure 9 is an enlarged section on the line 9—9 of Figure 2 showing the work spindle supporting mandrels,

Figure 10 is an enlarged section on the line 10—10 of Figure 9 showing the work mandrel holding means, and

Figure 11 is a fragmentary detail view in side elevation of the cams used to actuate the grinder in rocking motion.

Referring to the drawings in detail, 15 indicates the top of a frame 16 in which the machine is mounted. Journal brackets 17 support the work carrier shaft 18^A upon which is mounted spaced disk plates 18 separated by the spacing sleeves 19 intermediate which are held the pulleys 20 located midway between the plates 18, and fastened in any suitable manner to the shanks 21 of fluted work supporting spindles 22, the latter of which project from one face of the plate 18 toward the observer looking at Figure 2. The spindles are arranged peripherally about the edge of the plate 18 and as the plate revolves, by means later to be described, they have an orbital travel and rotate axially through the drive of the pulleys 20 which are engaged by the drive belt 23 only at one side of the shaft 18 so that the spindles as they rotate in clockwise direction in their orbit will be axially rotated by the belt 23 in a section designated as the working area or grinding zone. The belt 23 passes over the upper and lower pulleys 24 fixed to stub shafts 25 in a bracket 26, the lower shaft 26 having an added pulley 27 which is connected for drive through a pulley 28 and belt 29 with a driven countershaft 30. The pulley 28 is disposed on the shaft 30 beneath the table top, the belt 29 operating through a suitable opening in the top, from which the shaft 30 is suspended in the brackets 31.

The drive pulley 28 and countershaft are operated by a motor 32 whose shaft 33 is connected for drive to shaft 30 through worm 34, worm wheel 35, cross shaft 36 and bevel gearing 37, the parts being hereafter referred to as a driving train of parts. The shaft 33 also carries an outer pulley wheel 38 the driving effort of which is transferred to the pulley wheel 40 through the medium of belts 41 and 42 and an intermediate speed regulating device 44 of well known con-

struction. The adjustable speed jack 44 is mounted in a bracket 45 and the latter is extended to provide bearings for a shaft 46 upon which said pulley 40 is fixed and a gear shaft or cam shaft 47, which through a gear 48 and pinion 49 is actuated from the shaft 47.

The shaft 47 carries adjacent the center of the machine, spaced cams 50 and 51 and at one end a bevel gear 52 for the operation of an obliquely disposed shaft 53 through a pinion 54. Said shaft 53 carries a cam 55 the purpose of which will be later described, and at its upper end a pinion 56 which operates a bevel gear 57 secured to the end of a cam stud shaft 58 journaled in a bracket 59 which also has journalled therein one end of work carrier shaft 18. Shaft 18 carries a Geneva wheel 60 having a pin socket 61 for each of the spindles on the work carrier plates 18, whereby with each rotation of the stud shaft 58, a pin 62 mounted in a disk 63 carried on said shaft will engage a socket of the Geneva wheel and rotate the work carrier to advance the work one increment which as illustrated herein happens to be one eighth the circumference of the carrier. In this manner, the work carrier plates 18, referred to for convenience as the work carrier (Figure 6), advances from station 1 where the blank cork W is impaled on a spindle 22 to station 2 where the blank is pressed home on the spindle by a mechanical device to be later described, then to stations 3 and 4, at the latter of which the blank receives its first or rough grinding, then to stations 5 and 6 at the latter of which fine or finish grinding occurs, then to stations 7 and 8 at the latter of which the finished article is drawn from the spindle by means to be later described and dropped into a receptacle or onto a conveyor as desired.

The grinding is accomplished by the use of a rough grinding wheel 65 and a fine grinding wheel 66. Each wheel is mounted in a rocker, the upper or coarse wheel 65 being carried on a shaft 67 journalled in bearings 68 secured to the plate portions 69 of the upper rocker 70, whose sleeve swings on the upper shaft 71 when a rearwardly extending rock arm 72 is oscillated by the raising and lowering action of cam 51 (Figs. 2 and 11) transmitted to said rock arm through a cam roller carrying bar 73 mounted for vertical sliding movement in a slide bracket 74 on the table top, and connected to said rock arm by an adjustable link 75. The finish or lower grinding wheel 66 is carried on a shaft 76 journalled in bearings 77 secured to the plate portions 78 of a lower rocker 79 whose sleeved portion 80 swings on a lower shaft 81, which with shaft 71 is mounted in brackets 82 presenting plate portions 83 in which pulley shafts 84 and 85 are mounted. The grinding wheel is advanced and retracted with respect to the work in the same manner as is the upper wheel, when a rock arm 86 extending from said sleeve 80 is oscillated by the raising and lowering action of a cam 50 transmitted to said rock arm through a cam roller carrying arm 87 mounted for vertical sliding movement in a slide bracket 88 on the frame top 15 and connected to the rock arm 86 by an adjustable link 89. The grinding wheels are driven by an upper belt 90 and a lower belt 91 from belt wheels 92, 93 mounted on countershaft 94 supported on the brackets 95 at the rear of the machine looking from the feed end. The wheels 92, 93 are driven from the motor shaft 33 through a belt 96 operating a drive pulley 97 fixed to shaft 94. The upper belt 90 passes about pulley 92, beneath pulley 98 on shaft 85

and around pulley 99 on shaft 67. The lower belt 91 passes about pulley 93, over the pulley 100, on shaft 84 and around a pulley 101 on shaft 76, to drive the grinding wheel 66.

As the movement of the work carrier is intermittent, the operation of all of the cooperating parts is synchronised with the movement of the carrier and at station 1 during the dwell between advance movements of the carrier, the operator presses a cork blank against the sharp end of the spindle and the latter is supported thereon. The spindle coming from station 8 is empty, the finished article having been taken from the spindle by a claw member 102 of U-shape fixed on the end of a slide bar 103 and presenting at the outer free ends of the member 102, the adjustable tongue pieces 104 which may be adjusted through the screw and slot connection 105 to engage work of varying dimensions in a withdrawing movement to pull the work from the spindle.

When the new work reaches station 2, it is pressed fully onto the spindle by a pusher 106 whose threaded shank 107 affords adjustment of the pusher relatively to the slide bar 108 which carries said pusher or work positioner. Both slide bars 103 and 108 are mounted for reciprocatory movement in guides 109 of a bracket 110 mounted on the machine top 15. Both slide bars are connected by a lever 111 pivoted intermediate the bars as at 112 to the bracket and the lower bar 108 where it is connected to the lever 111 is also pivoted as at 113 to an operating lever 114 connected by a link 115 to the end of a cam bar 116 which slides in a rest 117 and is actuated by a cam end 118 carrying a cam roller 119 in engagement with the cams 56A which latter imparts one reciprocation to the slide cam bar 116 at each revolution of the shaft 58. Through this medium, the upper and lower slides 103, 108 are reciprocated, the upper one to push the work completely onto the spindle and then retract and the lower one to cause the claw to retract to pull the finished article off spindle station 8 and then advance as the pusher retracts. Grinding occurs at stations 4 and 6 and the pressure of the grinders on the work might result in the breaking off of the spindles and to steady the work and true it as well as prevent breakage of the spindles, use is made of upper and lower chucks 120 both of which are alike in construction and are shown in Figure 10. Each chuck 120 consists of a body portion 121 and a rotary cap 122 separated by a roller bearing, the cap and body being bored as at 123 to receive the sharp end of the spindle and form a journal therefore. The body forms one end of a shank 124 which passes through a flanged bushing 125 fast in a bracket plate 126 attached to the journal bracket 17. The shank is shouldered as at 127 to abut the face of a presser plate 128 and is surrounded by a spring which extends from the end of the bushing 125 to the plate 128, the spring 129 tending to retract the shank and the chuck, the shank being attached to the presser plate 128 by the threaded stud end 130 of the shank 124 and a nut 131. The chucks are fed toward the spindles by pressure applied to the presser plate by a roller 132 carried on a presser arm 133 pivoted at one end to an ear of the bracket plate indicated as at 134. The depending lever arm 133 has pin and slot connection as at 135 to a cross slide bar 136 which rests in suitable supports 138 and is actuated by a cam link 139 carrying a cam roller 140 in engagement with the cam 55 which imparts one reciprocation to the bar 136 with

each revolution of the shaft 53. During the grinding operations the spindles are thus effectively supported.

The adjusting links 75 and 89 can be manipulated to adjust the throw of the wheels individually so that the depth of grind can be closely controlled. The advantage gained in the structure set forth is in bringing the rotating work orbitally to the grinding wheels and bringing the grinding wheels also to the work so that the work and the wheels are rotating at high speed and the grinding is quickly performed both in making the rough grind and the finish grind, the work moves continuously from one station to another and progresses intermittently through the machine so that there is a steady output. If desired means may be used to feed the blanks to the starting point station 1 mechanically and position them automatically so that they will be ready for mounting on the spindles without the attention of an operator.

Our invention is not to be restricted to the precise details of construction shown since various changes and modifications may be made therein without departing from the scope of the invention or sacrificing the advantages to be derived from its use.

What we claim is:

1. In a grinding machine, in combination, a work holder presenting a plurality of pulley bearing spindles upon which the work is positioned, means for moving the holder to bring the spindles successively to position the work for grinding, means for rotating the spindles as they reach grinding position including a constantly operating belt with which the pulleys of said spindles have driving contact when the spindles are at grinding position, grinding wheels, and rockers for moving the wheels toward and away from the work for engaging the latter during rotation of the spindles at successive grinding stations simultaneously.

2. In a grinding machine, in combination, a work holder presenting a plurality of pulley bearing spindles upon which the work is positioned, means for moving the holder to bring the spindles successively to position the work for grinding, means for rotating the spindles as they reach grinding position including a constantly operating belt with which the pulleys of said spindles have driving contact when the spindles are at grinding position, grinding wheels, rocking means for moving the grinding wheels into and out of contact with the work at a plurality of successive grinding stations simultaneously when the work is in grinding position, and means for supporting the free ends of said spindles during the grinding operations.

3. In a grinding machine, in combination, a work holder including spindles arranged in circular order, means for moving the holder to bring the spindles successively to work receiving, work grinding and work discharge positions, means for forcing the work onto a spindle at the feed positions, means including rock arms and wheels carried by said arms for grinding the work at a plurality of grinding positions simultaneously, retractable means for engaging and supporting the

ends of said spindles at each of said grinding positions and means for removing the work from the spindle at the work discharge position.

4. In a grinding machine, in combination, a work holder including spindles arranged in circular order, means for moving the holder to bring the spindles successively to a work receiving position, a plurality of work grinding positions and a work discharge position, means for impaling the work on a spindle at the feed position, means for grinding the work at the grinding position, retractable means movable to engage and support said spindles at said grinding positions, means for removing the work from the spindles at the work discharge position, and operating means associated with said work forcing and said work removing means whereby the work is impaled on one spindle as it is removed from another spindle.
- 20 5. In a grinding machine, in combination, a work carrier including work supporting spindles, means for moving the carrier to bring the work on the spindles successively to different grinding stations, grinding wheels, means for moving said wheels toward and away from the work including rockers and cam actuated arms for oscillating the rockers, means for individually adjusting said arms for varying the amount of movement of each of said wheels toward and away from the work whereby the depth of the grinding action can be closely controlled and retractable means for engaging and supporting the outer ends of said spindles during the grinding action.

- 30 6. In a grinding machine, in combination, a work carrier including work supporting spindles, means for moving the carrier to advance the work successively from a feed to grinding and discharge stations, means for positioning the work on the spindles at the feed station, means for grinding the work at a grinding station, means for removing the ground work at the discharge station, said work removing means comprising a claw member through which the spindles may pass to position the work within the claw, and tongues on the said claw member for engaging the work and removing the same from the spindle and means for adjusting said tongues to accommodate the claw member to work of varying size.
